UNITED STATES PATENT OFFICE.

HENRY YOE, OF DETROIT, MICHIGAN, ASSIGNOR TO DETROIT STEEL PRODUCTS COMPANY, OF DETROIT, MICHIGAN, A CORPORATION OF MICHIGAN.

SASH-CENTER.

992,326.

Specification of Letters Patent. Patented May 16, 1911.

Application filed October 31, 1910. Serial No. 590,026.

To all whom it may concern:

Be it known that I, HENRY YOE, a citizen of the United States of America, residing at Detroit, in the county of Wayne and State 5 of Michigan, have invented certain new and useful Improvements in Sash-Centers, of which the following is a specification, reference being had therein to the accompanying drawings.

10 The invention relates to sash centers particularly designed for use in swinging window construction, and the invention consists in the construction as hereinafter set forth.

In the drawings,—Figure 1 is a perspective view of the two members of the sash center detached; Fig. 2 is a cross section through the members engaged and secured to the sash and frame respectively; Fig. 3 is a section on line $x-x$ Fig. 2.

20 A is one member of the sash center which is provided with a circular disk shaped base B and a central pintle C preferably integral therewith.

D is a coöperating member which is of 25 similar form but is provided with a laterally extending peripheral flange E and a central hub F which is apertured at G to receive the pintle C. The member D is further provided with an entrance slot H for 30 the pintle C which extends into the aperture G of the hub.

To hold the members A and D normally in concentric relation to each other, the former is provided with a projecting lug 35 which fits within the flange E. As preferably constructed a pair of lugs I and I' are arranged upon diametrically opposite sides of the disk B and each lug is fashioned to have one end fit within the flange E and the 40 other end to extend adjacent to the hub G. The lugs are restricted in width so as to easily enter the slot H when in alinement therewith, and a very slight turning of the centers will cause the ends of the lugs to engage with the flange or hub so as to hold the 45 members in concentric relation.

The members A and D may be secured respectively to the sash and frame of the window by screws which engage countersunk 50 apertures J in the disks. These apertures in

the member A are preferably located in the center of the lugs I and I'.

One of the advantages of the construction is that the centers are held in engagement with each other for the greater part of the 55 angular adjustment of the window, thereby avoiding danger of accidental disengagement.

What I claim as my invention is:

1. A sash center, comprising a pair of co-operating members, one of said members being provided with a central pintle and the other with an apertured hub for receiving said pintle and a concentric surrounding annular flange, a lug on the first mentioned 60 member extending between the flange and hub of the coöperating member and engageable therewith through an entrance slot in the latter member, said pintle being engageable with said hub through said entrance 65 slot.

2. A sash center, comprising a pair of co-operating members, one being provided with a central pintle and the other with a hub apertured to receive said pintle and a surrounding concentric annular flange, a pair 70 of lugs on diametrically opposite sides of the first mentioned member adapted to fit between the hub and flange of the coöperating member, said coöperating member being provided with an entrance slot for said lugs 75 and said pintle.

3. A sash center, comprising a pair of co-operating members, one being provided with a central pintle and the other with an apertured hub and a surrounding concentric annular flange, a pair of lugs on diametrically opposite sides of the first mentioned member adapted to fit between the hub and flange of the coöperating member, said coöperating 85 member being provided with an entrance slot for said lugs and pintle into the aperture in said hub, and a slot through the opposite side of said hub for the passage of one of said lugs. 90

4. A sash center comprising a pair of co-operating members, one of said members being provided with a central pintle and the other with a bearing for receiving said pintle apertured to permit the engagement of 100

the pindle therewith by a relative lateral movement of said coöperating members, and means operable upon the rotation of one of said members for preventing relative lateral movement between said members comprising an annular flange upon one member having a recess therein, and a projection upon the other member positioned to have a bear-

ing on said flange and engageable therewith through said recess. 10

In testimony whereof I affix my signature in presence of two witnesses.

HENRY YOE.
